US00D995514S

(12) **United States Design Patent** (10) **Patent No.:** **US D995,514 S**
Wu et al. (45) **Date of Patent:** **** Aug. 15, 2023**

(54) **COMBINED EARPHONE AND WATCH**

(71) Applicant: **Shenzhen Aukey Smart Information Technology Co., Ltd.**, Shenzhen (CN)
(72) Inventors: **Yuefeng Wu**, Shenzhen (CN); **Changxing Xia**, Shenzhen (CN); **Liang Chen**, Shenzhen (CN)

(73) Assignee: **Shenzhen Aukey Smart Information Technology Co., Ltd.**, Shenzhen (CN)

(**) Term: **15 Years**

(21) Appl. No.: **29/811,872**

(22) Filed: **Oct. 18, 2021**

(51) **LOC (14) Cl.** **14-02**

CLAIM

The ornamental design for a combined earphone and watch, as shown and described.

DESCRIPTION

FIG. 1 is a front perspective view of a combined earphone and watch, showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded perspective view thereof.

The broken lines in the drawings illustrate portions of the combined earphone and watch and form no part of the claimed design.

1 Claim, 9 Drawing Sheets
